(57) **CLAIM**
The ornamental design for a foam cleaning implement, as
shown and described.

DESCRIPTION

FIG. 1 is a top perspective view of a foam cleaning imple-
ment;

FIG. 2 is a top view of the foam cleaning implement shown in
FIG. 1;

FIG. 3 is a right side view of the foam cleaning implement
shown in FIG. 1;

FIG. 4 is a left side view of the foam cleaning implement
shown in FIG. 1;

FIG. 5 is a front view of the foam cleaning implement shown
in FIG. 1;

FIG. 6 is a rear view of the foam cleaning implement shown
in FIG. 1; and,

FIG. 7 is a bottom view of the foam cleaning implement
shown in FIG. 1.

The broken line showing is included for the purpose of illus-
trating and forms no part of the claimed design.

1 Claim, 2 Drawing Sheets
